CLARENCE S. PINKERTON, OF MILWAUKEE, WISCONSIN, ASSIGNOR, BY MESNE ASSIGNMENTS, TO CUTLER-HAMMER, INC., A CORPORATION OF DELAWARE

AUXILIARY TIMING DEVICE

Application filed February 5, 1927. Serial No. 166,146.

This invention relates to improvement in auxiliary timing devices, and the invention more particularly relates to the provision of such a device having an extremely wide range 5 of adjustability.

In many types of cooperating control instrumentalities it is necessary to provide a time lag in the response of one element with respect to that of another element, and in 10 some instances the required time element is so great as to render the use of reduction gearing or the like impracticable. Moreover, it is desirable to provide such devices with means for readily and accurately adjusting 15 the time of response of the respective elements through a wide range, and an object of my invention is to provide simple and efficient means for accomplishment of the aforementioned desirable results.

20 Other objects and advantages of the invention will hereinafter appear.

The accompanying drawing illustrates an embodiment of my invention and I have shown one mode of application thereof; but 25 it is to be understood that the invention is susceptible of other applications, and that the details of construction and operation thereof may be modified without departing from the spirit and scope of the appended 30 claims.

In the drawing, Figure 1 is a schematic and diagrammatic view of remote pressure control means for a valve, said means having my auxiliary timing device applied thereto to 35 modify the operative characteristics thereof; and

Figs. 2 and 3 are, respectively, detail top plan and side elevational views of certain control elements including my auxiliary timing device.

As shown in the drawing the device comprises essentially a continuously rotatable power driven shaft 10 having a drum 11 of insulating material, such as wood, secured 45 thereto. Said drum carries a conductive strip or segment 12 which is adapted to bridge a pair of contact fingers 13 and 14 once during each revolution of the drum. A bracket 15 is rigidly secured to drum 11, as 50 by means of screws 16, and said bracket is

provided with a slot 17 arranged radially with respect to the axis of drum 11 and shaft 10. A bolt or rod 18 is slidable in slot 17 to provide for concentric positioning or any desired degree of eccentric positioning of 55 said bolt with reference to the axis of said drum. Head 19 of bolt 18 and a sleeve 20 are adapted for clamping engagement with opposite surfaces of bracket 15, said sleeve being forced into clamping position by a thumb nut 21 on the threaded shank of bolt 18. If desired a washer 22 may be interposed between nut 21 and sleeve 20. Sleeve 20 also serves as a pivot bearing for a pawl 60 or dog 23, said pawl being biased by means of spring 24 into engagement with a toothed wheel or ratchet 25.

Wheel 25 is fixed to a shaft 26, said shaft being in turn supported in the upstanding arms 27 and 28 of a U-shaped bracket 29 secured to a suitable base member 30 by means of screws 31. Also secured to shaft 26 and rotatable with wheel 25 is a cylindrical member 32 having a plurality of equally spaced tapped openings 33, whereby one or more 65 studs or pins 34, having threaded shanks 35, may be removably secured to said member 32.

A pair of cooperating spring contact fingers 36 and 37 are provided, and contact finger 36 is normally biased out of engagement with contact finger 37, as indicated by dotted lines in Fig. 3, and upon a given degree of rotation of cylinder 32 a pin 34 is adapted to engage a projection on the end of contact finger 36 to effect engagement of the latter with contact finger 37, as will be obvious.

70 Contacts 36 and 37 are secured to the under side of an insulating block 38, as by means of bolts 39 and 40, respectively; suitable nuts 41 being provided for securing said bolts, and for clamping the circuit wires thereto. Block 38 is superimposed upon an insulating block 42, and said blocks are jointly secured to insulating blocks 43 by means of screws 44, the latter blocks being secured to base 30 by 75 means of a suitable number of screws 45. Contacts 13 and 14 are yieldably supported in a well known manner by conductive members 46 and 47, respectively, the latter being secured to block 42 by means of bolts 48 and 80 85

49 forming terminal binding posts therefor. As will be apparent the block 38 overhangs blocks 42 and 43 to provide clearance for contacts 36 and 37.

If desired, a suitable cover or housing 50 may be provided for the parts thus far described.

Assuming operation of shaft 10 at a substantially constant speed, and further assuming connection of contacts 13-14 and 36-37 10 in a manner to require joint closure thereof to complete the circuit, it is obvious that a very wide range of adjustment of the periods between joint closure of said contacts is provided. Thus, with contacts 36-37 held in 15 closed position as best shown in Figs. 2 and 3, bolt 18 of pawl 23 may be adjusted to a position concentric with the axis of drum 11, thus rendering said pawl inoperative to move cylinder 32 out of the position illustrated. 20 With this arrangement completion of the circuit will depend solely upon the time required to effect one revolution of drum 11, which time in practice may be about fifteen seconds.

By securing a single stud to cylinder 32 25 and by adjusting pawl 23 to effect movement of wheel 25 one notch upon each operation of said pawl, and assuming employment of a wheel 25 having sixty teeth, the time required for effecting completion of the circuit 30 will be increased sixty fold over that aforementioned, or fifteen minutes.

Also obviously pawl 23 may be rendered inoperative in the foregoing manner with 35 cylinder 32 so positioned as to permit opening of contacts 36-37, thus providing for continuous interruption of the circuit notwithstanding intermittent closure of contacts 13-14.

The timing intervals may therefore be varied within the wide range indicated by varying the number and arrangement of studs 34 40 on cylinder 32, and by adjusting pawl 23 to provide for movement of cylinder 32 through a different number of peripheral spaces as 45 measured by the ratchet teeth on wheel 25.

As will be apparent to those skilled in the art the timing means described is susceptible of wide application as auxiliary control means for circuit makers and breakers which 50 include a member operable at a substantially constant rate or speed. For example, in Fig. 1 I have illustrated my invention as applied to the control of a remote pressure regulating valve in a fluid distributing pipe line or system. Obviously, however, the control may be applied to a primary pressure producing device, in which case the valve 59 would be omitted. The control means as shown may 55 comprise a balanced pressure bell or float 51 having an arm of conductive material pivoted at 52 and having a contactor 53 adapted to engage stationary contacts 54 or 55 under given pressure conditions as hereinafter described. A small pipe 56 leading from con-

duit 57 communicates with the interior of bell 51, the lower end of said bell being immersed or sealed in a liquid carried by a container 58.

The other control elements now to be described are preferably located at a point adjacent to the pressure regulating valve or district governor 59, which latter may be as much as ten miles or more away from bell 51 and its associated contacts. Thus I have shown a ratcheting device of well known form, said device comprising a motor 60 adapted to be supplied with current from a suitable source and to be operated at substantially constant speed. Motor 60 drives ratcheting levers 61 and 62 through suitable reduction gearing and motion translating mechanism indicated generally at 63, said levers carrying pawls 64 and 65 adapted upon energization of the windings 66 or 67, respectively, to engage and effect movement of wheel 68 in one direction or the other.

Secured to and rotatable with wheel 68 is a shaft 69 carrying a spool or drum 70 for winding or unwinding a cord or cable 71, said cable being connected at one end to said drum, and being connected at its other end through the medium of a tension spring 72, to a lever 73 pivotally supported at 74 and pivotally connected at 75 to the operating lever of valve 59. The degree of opening of valve 59 may be manually preset or adjusted by means of an adjustable counterweight 76. Shaft 10 of the auxiliary timing device is adapted to be driven by motor 60 through the aforementioned gearing 63, the details of said timing device having been heretofore described in connection with Figs. 2 and 3.

Thus with valve 59 adjusted to provide for a given rate of flow of fluid from main 77 through conduit 57, such adjustment will be maintained pending variation in the demand for fluid from said conduit. However, upon an increase in the fluid demand there will be a resultant decrease in the pressure of the fluid in conduit 57 which will cause lowering of the bell or float 51. After a given degree of lowering of said bell, contactor 53 is brought into engagement with contact 54, thereby tending to complete the energizing circuit of ratchet solenoid winding 67. As aforeindicated said circuit will be completed immediately upon concurrent closure of contacts 36-37 and bridging of contacts 13-14.

Said circuit may be traced from line L¹ to contactor 53 and contact 54, by conductor 78 through solenoid winding 67, conductors 79 and 80, contact 13, segment 12 and contact 14, conductor 81, contacts 36 and 37 to line L². Pawl 65 is thus brought into engagement with ratchet wheel 68 to effect a predetermined degree of rotation of the latter in a counterclockwise direction, which in turn effects a given degree of unwinding of

cable 71 from drum 70 with consequent opening of valve 59 to vary the supply of fluid to conduit 57.

After one operation of ratchet wheel 68 by pawl 65 the energizing circuit of winding 67 is interrupted through movement of segment 12 out of engagement with contacts 13 and 14 and also through movement of the last mentioned stud 34 out of engagement with contact 36. As is well known if the pressure responsive device 51 is located about ten miles away from valve 59 it will require about one and one-fourth minutes for the pressure effect of the valve adjustment to traverse said distance. Accordingly the timing elements aforescribed will be adjusted to provide against re-completion of the energizing circuit of winding 67 during such period.

If the aforementioned automatic adjustment of valve 59 has been sufficient to restore the predetermined pressure in conduit 57 prior to the next period of coincident reclosure of contacts 36-37 and 13-14, bell 51 will have been returned to normal position with consequent movement of contactor 53 out of engagement with contact 54, so that the energizing circuit of winding 67 cannot be completed. On the other hand if bell 51 remains in a position to effect continued engagement of contactor 53 with contact 54 such coincident reclosure of contacts 36-37 and 13-14 will again complete the energizing circuit of winding 67 with consequent further automatic adjustment of valve 59. Such operation will be continued until the desired predetermined pressure has been restored in conduit 57, as will be obvious.

Similarly if the demand for fluid from conduit 57 is decreased the pressure therein will be increased to effect lifting of bell 51 from normal position with consequent engagement of contactor 53 and contact 55; whereas under these conditions upon simultaneous closure of contacts 36-37 and 13-14 an energizing circuit for solenoid winding 66 is completed. Said circuit may be traced from line L¹ to contactor 53 and contact 55, conductor 82 through said winding, conductors 83 and 80 to contact 13, segment 12 and contact 14, conductor 81 to contact 36 and contact 37 to line L². Pawl 64 is thus brought into engagement with ratchet wheel 68 to effect a given degree of movement thereof in a clockwise direction with consequent winding of cable 71 upon spool 70 to partially reclose valve 59. Said operation is repeated after a given time interval depending upon the adjustment of pawl 23 and the angular position of the next succeeding stud 34, provided the contactor 53 has not been disengaged from contact 55 due to normal positioning of bell 51 as aforescribed.

While I have shown contactor 53 as adapt-

ed to engage with single contacts 54 and 55 on opposite sides of the neutral position thereof, it is to be understood that a multiple-contact arrangement such as that disclosed in the patent of Packard and Schmidt, No. 1,700,852, dated Feb. 5, 1929, may be employed if desired; said multiple-contact device including suitable electromagnetic means for effecting intermittent clamping of a movable member between the contact elements, as described in said patent.

I have thus provided means for simply and accurately varying the timing intervals according to the particular conditions to be met with in a given installation, whereas obviously if desired suitably calibrated indicia may be provided on bracket 15 and on cylinder 32 to facilitate the adjustments aforesaid.

Referring more particularly to Fig. 1, it will be understood that the driving connection between wheel 68 and spool 70 preferably includes suitable worm gearing, whereby said spool is held in its respective adjusted positions against the bias of spring 72 and counterweight 76.

Moreover, it will be noted that the operation of segment 12 with respect to contacts 13-14 provides for a relatively quick make and break of the control circuit under all conditions, thereby relieving all of the contact elements from the deleterious effects of arcing.

What I claim as new and desire to secure by Letters Patent is:

1. In an auxiliary timing device, in combination, a power operated drum and contacts to be intermittently closed thereby, contacts included in circuit in series with said first mentioned contacts, and means for effecting intermittent closure of said second mentioned contacts, said means comprising a pawl and ratchet mechanism having a driving connection with said drum and a rotating element driven by said mechanism.

2. In an auxiliary timing device, in combination, circuit controlling means including a power operated contactor tending to complete an electric circuit at predetermined intervals, means for rendering said contactor ineffective for completing the circuit pending closure of a pair of contacts connected in circuit in series therewith, and means for effecting closure of said contacts at predetermined intervals, said means comprising a rotatable member having one or more projections thereon for intermittent engagement with said contacts, pawl and ratchet mechanism for effecting rotation of said member, and an adjustable driving connection between said contactor and said pawl and ratchet mechanism.

3. In an auxiliary timing device, in combination, circuit controlling means including a rotatable contactor to be driven at substan-

tially constant speed and tending to complete an electric circuit at predetermined intervals, a pair of normally open contacts included in circuit in series with said contactor, means for rendering said contactor ineffective for completing the circuit pending closure of said contactor and said contacts jointly, said means comprising a rotatable member having a plurality of independently removable studs projecting therefrom to intermittently engage certain of said contacts for effecting closure thereof, pawl and ratchet mechanism for effecting rotation of said member, and an adjustable driving connection between said contactor and said pawl.

4. In a timing device, in combination with a standard type of power operated ratcheting mechanism and electroresponsive means adapted when energized to render said mechanism effective, of means comprising a contact drum driven in synchronism with said ratcheting mechanism and tending to effect energization of said electroresponsive means at predetermined intervals, means comprising a pair of normally open contacts connected in series with the contacts of said drum to render the latter ineffective pending closure of the former, a member rotatable in proximity to certain of said normally open contacts, one or more studs carried by said member to intermittently engage and close said contacts, a pawl and ratchet mechanism for effecting rotation of said member, and an adjustable driving connection between said drum and said pawl and ratchet mechanism.

5. In a timing device, the combination with a power operated ratcheting mechanism and a plurality of electroresponsive devices adapted when energized individually to effect operation of said mechanism in opposite directions respectively, of an automatically operable switch having a neutral position and tending when moved in opposite directions from said position to complete an energizing circuit for one of said electroresponsive devices, a contact drum driven in synchronism with said ratcheting mechanism and tending to intermittently complete and interrupt said circuit, a pair of normally open auxiliary contacts included in series in said circuit and means for intermittently closing and opening said contacts, said means comprising a member rotatable in proximity to certain of said contacts, a plurality of studs carried by said member and adapted to engage said contacts, and an adjustable driving connection between said contact drum and said member.

6. In a timing device, the combination with a power operated ratcheting mechanism and a plurality of electroresponsive devices adapted when energized individually to effect operation of said mechanism in opposite directions respectively, of a pressure operated switch having a neutral position and tending when moved in opposite directions

from said position to complete an energizing circuit for one of said electroresponsive devices, a contact drum driven in synchronism with said ratcheting mechanism and tending to intermittently complete and interrupt said circuit, a pair of normally open auxiliary contacts included in series in said circuit and means for intermittently closing and opening said contacts, said means comprising a member rotatable in proximity to certain of said contacts, a plurality of spaced studs carried by said member, means for varying the number and spacing of said studs, and means for adjustably connecting said member with said contact drum to be driven thereby, said means comprising a ratchet wheel secured to said member and a pawl pivotally supported by said drum and adjustable eccentrically to different degrees with reference to the axis of the latter.

7. In a timing device for remote pressure control systems, in combination, a contactor operable in accordance with variations in pressure at a given point in the supply line, a pressure regulating valve located in said line at a distance from said contactor, electroresponsive means located adjacent to said valve for effecting operation of the latter, means tending to complete the energizing circuit of said electroresponsive means upon operation of said contactor, a pair of normally open contacts requiring closure thereof to complete said circuit, power operated means for effecting closure and opening of said contacts at predetermined intervals, and adjusting means associated with said last mentioned means for varying the time of closure and opening of said contacts.

8. In a timing device for remote pressure control systems, in combination, a pressure regulating valve, automatically operable means tending to effect adjustment of said valve in steps, a pressure responsive device located at a distance from said valve and said adjusting means for controlling the latter, and means for timing the operation of said adjusting means in accordance with the distance between said valve and said pressure responsive device, whereby the latter is subjected to the pressure effect of a given adjustment of the former prior to a repeated operation of said adjusting means.

9. In a timing device for remote pressure control systems, in combination, a pressure regulating valve, automatically operable means tending to effect adjustment of said valve in steps, a pressure responsive device located at a distance from said valve and said adjusting means for controlling the latter, and means for timing the operation of said adjusting means in accordance with the distance between said valve and said pressure responsive device, whereby the latter is subjected to the pressure effect of a given adjustment of the former prior to a repeated opera-

tion of said adjusting means, said timing means comprising a plurality of sets of contacts included in series in an electric circuit and adjustable means for varying the time of closure of said contacts jointly.

- 5 In witness whereof, I have hereunto subscribed my name.

CLARENCE S. PINKERTON.
